UNITED STATES PATENT OFFICE

NORMAN H. KLAGES, OF PITTSBURGH, PENNSYLVANIA, ASSIGNOR TO G. W. KLAGES & SON, INC., A CORPORATION OF PENNSYLVANIA

GRINDING MACHINE

Application filed November 3, 1928. Serial No. 317,008.

The invention relates to grinding machines, and particularly to machines for grinding the edges of sheets of material; such as glass and marble. The invention has for its objects, 5 the provision of an improved work spindle and drive for the annular grinding wheel employed, permitting the convenient and accurate adjustment of the grinding wheel from time to time to compensate for the wearing 10 away of the abrading surface of the wheel, and the provision of a machine having an improved table or support for the sheets, whose edges are to be ground, arranged so that the table may be tilted so as to give any 15 desired bevel upon the sheets without materially shifting the position of the edge of the table or sheet with respect to the cutting surface of the abrading disc or wheel, thus permitting such disc or wheel to work at its 20 most advantageous cutting position, regardless of the angle at which the table is tilted. One embodiment of the invention is illustrated in the accompanying drawings, wherein:

25 Figure 1 is an end elevation of the machine, and Fig. 2 is a partial side elevation and partial section.

Referring to the drawings, 1 is the base of the machine which is a relatively heavy rigid 30 casting and 2 is a table mounted for reciprocation on the roller bearings 3, 4 and 5, such table being reciprocated by the piston rod 6 operated by a suitable hydraulic power ram having the necessary range of stroke. Carried upon the table is the motor 7 which drives the disc grinding or abrading wheel 8 by means of the spindle 9. A suitable casting 10 encloses the spindle and wheel with a receptacle 11 for catching the water which is 35 supplied to the wheel from the pipe 12.

40 The spindle 9 is journaled in the sleeve 13 by means of the bearings 14 and 15, which sleeve is threaded through the block 16 carried by the bed 2, thus permitting of the adjustment of the disc 8 to compensate for wear. The sleeve is rotated by means of the worm wheel 16^a splined to the sleeve and engaged by a worm 17 rotated by the crank 18. The worm wheel 16^a has its hub swivelled, as shown, to 45 the block 16^b bolted to the bed 2. The left

hand end of the spindle 9 is splined in the coupling block 18' (driven from the motor 7), thus permitting of the endwise adjustment of the sleeve 13 and the spindle carried thereby.

55 Mounted in front of the grinding wheel 8 is the means for supporting the sheets whose edges are to be ground or smoothed. This means comprises the two standards 19, 19 mounted on the base 1, the brackets 20, 20 mounted for angular adjustment on the standards, and the plate 21 pivoted at 22, 22 to the brackets 20, 20. The standards 19, 19 and brackets 20, 20 have opposing flat surfaces at 23 in sliding engagement, and the brackets are provided with the racks 24, 24 fitting in slots in the faces of the standards. These racks are engaged by a pair of pinions 25, 25 on the transverse shaft 26 journaled 60 in the standards. By rotating the shaft, the brackets may be adjusted up and down. The shaft 26 is provided with a squared portion 26^a (Fig. 1) to which a wrench may be applied to rotate the shaft. In order to clamp the brackets in adjusted position, the bolts 26^b are employed (Fig. 2), such bolts being 65 screwed into the standards 19 and having their shanks lying in slots in the brackets 20. The plate 21 has pivoted to its ends the slotted links 27, 27 and through the slots in these 70 links extend the studs 28, 28 mounted in the upper ends of the standards 19, 19. The studs are threaded and carry the nuts 29, 29 which serve to clamp the links in any desired 75 position of adjustment. The dotted lines show the plate 21 and links in one position of adjustment and the full lines show the plate and links in another position of adjustment.

80 When it is desired to face off the plate 30 of glass so that its edge is at right angles to its sides, the plate 21 and links 27 occupy the positions shown in full lines, and the table 2 is reciprocated back and forth on the bed 1 to carry the edge of the plate across the 85 face of the grinding wheel 8, the wheel being slightly inclined so as to cut only on one side as is well-known in the art. At this time the rear edge of the plate 30 is held against movement by the stop members 31, 31 held in adjusted position on the rods 32, 32 by means 90 100

of set screws, the rods, themselves, being securely mounted and held on the under side of the plate 21 in any suitable manner. When wide plates are to have their edges ground, 5 the stop members 31 are removed and other members 33 and 34 are substituted, such members being shown in dotted lines. The members 34 constitute the stops, while the members 33 lie beneath the plate to be ground and 10 give it additional support.

When the plate is to be beveled, the plate 21 is tilted as shown in dotted lines, the links 27, 27 being locked in position by the nuts 29, 29, as heretofore explained. Any desired 15 angle of beveling may be secured by tilting the plate 21 the necessary amount. If the pivots 22, 22 of the plate 21 remained in the full line position shown, the tilting movement of the plate would carry the edge of the 20 plate 21 to the left and downward into interference with the periphery of the grinding wheel. The provision of the angular sliding support of the brackets 20, 20 in connection with the rack and pinion adjustment takes 25 care of this difficulty as the upward angular movement of the standards keeps the forward edge of the plate 21 at a proper position despite the movement of such edge due to the tilting of the plate as above described. 30 The rod 35 (Fig. 1) serves to shift the clutch which controls the back and forth movement of the bed 2, such rod being connected at its right hand end to the lever 36 carried on the shaft 37 and operated by the handle 38.

35 What I claim is:

1. The combination with a plate for supporting a sheet whose edge is to be ground, a supporting bed in front of said plate, a block carried by the bed, a sleeve threaded through 40 said block for endwise adjustment and provided upon its interior with bearings, a work spindle journaled in said bearings and movable endwise with the sleeve, a grinding wheel carried by said spindle, means for rotating the sleeve to adjust it endwise through 45 said block comprising a worm wheel splined to the sleeve and swivelled against axial movement relative to the bed, and a worm for rotating said wheel, a motor carried by the 50 bed and connecting means between the drive shaft of the motor and the spindle with which said spindle has a splined engagement to permit of the endwise adjustment of the spindle.

2. The combination with a driven annular 55 grinding wheel having its face in a substantially vertical plane, of a support for a sheet whose edge is to be ground, comprising standard means in front of the wheel having a guide face inclined upward and to the rear 60 at an acute angle to the vertical, bracket means having a face slidably engaging said guide face, interengaging means between the standard means and the bracket means for adjusting the bracket means on the standard 65 means, other means for locking the bracket

means in adjusted position, a plate pivotally supported for tilting movement about a horizontal axis on the bracket means and adapted to carry the sheet whose edge is to be ground, means for locking the plate in its tilted position of adjustment, and means for securing a relative movement in a horizontal direction transversely of the wheel between the standard means and the wheel, said axis about which said plate tilts being located adjacent 70 the forward edge of the plate.

75 In testimony whereof, I have hereunto subscribed my name this 19th day of October, 1928.

NORMAN H. KLAGES.
